UNITED STATES PATENT OFFICE.

GEORGE P. BOSWORTH, OF CENTRAL FALLS, RHODE ISLAND, ASSIGNOR TO HEMPHILL MANUFACTURING COMPANY, OF PAWTUCKET, RHODE ISLAND, A CORPORATION OF RHODE ISLAND.

STOCKING-KNITTING MACHINE.

1,209,255.

Specification of Letters Patent. Patented Dec. 19, 1916.

Application filed June 4, 1914, Serial No. 843,061. Renewed October 14, 1916. Serial No. 125,701.

To all whom it may concern.

Be it known that I, GEORGE P. BOSWORTH, citizen of the United States, residing at Central Falls, Rhode Island, have invented 5 certain new and useful Improvements in Stocking-Knitting Machines, of which the following is a specification.

In another application for Letters Patent of the United States, filed June 4, 1914, No. 10 843,060, I have described a circular stocking knitting machine for making a diagonal gore running at an inclination to the back of the stocking from a point preceding the heel pouch to the point where the narrowings for the regular heel pouch begins. The 15 present machine is designed to make this diagonal gore, and also what is known to the trade as the Hirner foot, this being referred to in an application for Letters Patent of 20 the United States filed by me April 11, 1914, #831296, and also in an application filed by Emile Bedard, April 11, 1914, #831,295, and consisting generally of the 25 introduction into the fabric of additional widening courses beyond the point where narrowing began, one result of which is that the foot will be knit at more nearly a right angle to the leg than is ordinarily done, and my present improvement utilizes features 30 contained in my application first above named, and in the Bedard application, certain modifications of said features being necessary and changes in their functions taking place in combining in the one machine these mechanisms for carrying out the 35 object of this invention.

In the accompanying drawings—Figure 1 is a diagrammatic view of a stocking made on the machine. Fig. 2 is a front view of 40 a knitting head embodying my invention. Fig. 3 is an end view of a part of the knitting head of Fig. 2, looking from the left of Fig. 2. Fig. 4 is a plan view of the machine in the nature of a diagram. Fig. 5 is a diagram of the needle cams developed.

The invention is shown in connection with the general type of machine known as the Banner, made under the Letters Patent of the United States issued to Hemphill 50 #933,443 of September 17, 1909, though it will be understood that the invention might be applied to other makes of machines, and I do not limit myself in this respect.

The needle cams include two stitch cams 55 1, 2, the cam 1 being in use when the ma-

chine is on round knitting and the needles are moving in the arrow direction Fig. 5, the needles being elevated to take the yarn by passing over the stitch cam 2. On reciprocating knitting for heel and toe work 60 first one stitch cam and then the other acts to draw the needles down, as in ordinary practice, for forming the stitches according to the direction in which the needle cylinder is rotating.

The instep lowering cam 3 performs its usual function of lowering the needles to normal plane after narrowing and widening has been accomplished. This cam is moved vertically by mechanism, hereinafter referred to, of ordinary form. With this cam is combined an instep needle raising cam 4, which is adjustable independently of the lowering cam 3, the said instep cam preferably being pivotally mounted at 5. It is 70 shown in its low position in Fig. 5.

At 6 is shown a fixed cam for raising the needles which have been partially raised by the switch or instep cam 4, this cam being arranged above the normal path 7 for the 80 needle butts.

In addition to the needle cams mentioned a supplemental needle raising cam is employed at 8, operated as hereinafter will be described. This cam 8 is on the outside of 85 the cam ring 9. The narrowing picks are indicated at 10 and the widening picks at 11.

The needles are divided into three sets in 90 respect to their lengths of butts, namely, short butt needles *a*, medium length butt needles *b*, *b*, and longer butt needles *c*. These longest butt needles *c*, however, are shorter than the long butt needles ordinarily employed, for instance in the regular Banner or like type of stocking knitting machine, and they are of a length to reach but slightly beyond the edge of the cam ring 9 where this is of usual thickness as indicated at 12. The length of these butts is 95 such that picking can be done upon them for narrowing and widening, and they are preferably about equal or but slightly longer than the short butt needles of the Banner machine upon which picking is done. These 100 longer butt needles *c* are the instep needles and they occupy one half of the needle circle, as shown in Fig. 4. The other half circle of needles is made up of the shortest butt needles *a*, (which, as a series, are arranged 110

diametrically opposite the series of long butt needles *c*) and the medium butt needles *b*. These medium butt needles are divided into two columns *b*, *b*, Fig. 4, one of said columns 5 lying at one end of the column of shortest butt needles and the other at the other end of the said short butt needles.

In round knitting for the leg or foot the needle cams are in the position shown in 10 Fig. 5, the needles passing in the arrow direction and their butts passing along the normal plane 7, being advanced to take yarn by riding over the cam 2, and being retracted to form the stitch by the cam 1. Now when 15 the gore is to be formed preceding the heel pouch and of the diagonal character indicated by the line *x*—*x'* Fig. 1, all the needles are raised to inoperative position to pass over both stitch cams and the guard cam 2', 20 excepting the shortest butt needles *a*, and for this purpose the cam 8 is elevated by connections hereinafter described. This cam, as shown in Fig. 4, sets in far enough to engage and lift both the medium butt needles, *b*, *b*, 25 and the longest butt needles *c*. The cam is shown down in Figs. 2, 3 and 5, and in fact all the figures represent the machine in the position at the end of the leg and foot before it is set to make the diagonal gore. This 30 cam having raised all the needles excepting the shortest butt needles *a*, immediately falls to normal position. At the same time the cam 8 is raised to raise the needles, as just described, the lowering cam 3 is also raised 35 and remains in its elevated position to avoid lowering any of the needles which have been raised to inoperative position. The machine now goes on to reciprocating work. The needles *a*, which remain down knit at the 40 back of the stocking, and on each stroke the widening picks pick down two of the elevated needles, these being the medium length of butts, and one of these is picked up by the narrowing picks as in ordinary practice, and 45 the fabric is gradually widened from the upper point *x* to the lower point *x'* in Fig. 1. When the diagonal gore is completed by widening to the lower point *x'*, the widening picks are lowered out of operation and the 50 narrowing picks continuing their picking action the fabric will be narrowed from *x'* to *y* for the regular heel pocket as in ordinary practice, after which the widening picks are brought into action again and the 55 fabric is widened from *y* to *x'*, as in usual practice, for the heel pocket. The point *x'* having been reached in widening the reciprocations of the needle cylinder are continued instead of, as in ordinary practice, 60 going on round knitting for the foot and the widening picks are continued in operation so that picking is now continued on the elevated longest butt needles *c*, which, as above stated are the instep needles. These needles, 65 as above described, have butts of such length

that picking can be done upon them, contrary to usual practice, and thus widening can be continued from *x'* to *z*, Fig. 1, thus producing what is known to the trade as the Hirner foot. During all the above actions 70 the instep cam 4 has remained in its low position, this cam contrary to usual practice being controlled independently of the lowering cam 3, the necessity for which will be clear when it is borne in mind that as picking is done on the longest butt needles, and as this cam is intended to act upon the longest butt needles it must be kept down out of operation, otherwise *i. e.* if it occupied its upper position, it would immediately raise 80 any long butt needle which had been picked down for widening. This cam, therefore, remains lowered during all the above described actions. After the additional widenings have been thrown in up to the point *z*, the 85 machine goes on round knitting for the foot. The lowering cam 3 is depressed and all elevated needles are thereby returned to normal plane 7.

Now when the toe is to be formed only the 90 instep needles *c*, (longest butts) are to be elevated to inoperative position, and then knitting goes on upon the heel and toe, or sole needles *a*, *b*, *b*, with the usual narrowing and widenings. The supplemental needle 95 raising cam 8 can not be used for elevating the needles which are to be inoperative in making the toe, because only the instep needles must be raised to inoperative position, whereas the said cam 8 would elevate 100 both the longest butt or instep needles and also the medium butt or heel and toe needles, therefore this cam 8 remains idle during the formation of the toe and in fact at all times excepting when it raises the long or medium 105 butt needles for the high splice as above described.

For raising the long butt instep needles in making the toe, the switch cam 4 is used, this being swung up from the position 110 shown in Fig. 5, at the same time the lowering cam 3 is elevated. The instep needles are raised by passing over this cam and are thus rendered inoperative, and the narrowing picks will now pick up or raise the medium butt needles, as in ordinary practice, for narrowing at the toe pocket, and then the widening picks, as in ordinary practice, will widen on these medium butt needles for the toe pocket, after which the machine goes 115 on round knitting. The cam 4, when it has elevated the instep needles returns to its low position.

The lowering cam 3 is mounted on a block 120 13, guided in a post or bracket 14 supported on the plate *H*, similar to that in the Hemphill Patent 933,443, September 7, 1909, and this block is moved vertically by a bell-crank lever 15, connected by a link 16 with the clutch lever *b'* of the Hemphill patent, 130

which is shifted by the pattern mechanism to change the drive from round and round to reciprocating, this connection being well known to those familiar with the Banner machine. The instep cam 4 may be of various forms and operated in various ways, but in the particular construction shown it is mounted on a shaft 5, journaled in a bearing on the post 14, and this shaft is operated by an arm 17, link 18, lever 19, and link 20, from cam lever 21, pivotally mounted at 22 on the machine frame, said cam lever being operated by a cam 23 on the pattern drum shaft s' of the Hemphill patent. This needle cam being shown down out of work, in the drawings, the lever 21 is resting on the low part of the cam 23, and it rests in this position during most of the revolution of the cam 23, being raised to elevate the needle cam 4 and raise the instep needles to inoperative position only when the high part 24 comes beneath it.

The supplemental needle raising cam 8 is guided in a box 25 fixed to the outer side of the cam or spacing ring 9, and it is raised by a pin 26 passing through a vertical slot 27 in the box and engaged by a lever 28 pivoted at 29 to the fixed bracket 30, the said lever being operated by a link 31, lever 32, pivoted at 33, a link 34 and a cam lever 35, which is pivoted at 22, and is acted on by a cam 36. In Fig. 3 the cam lever is shown as resting on the high part of the cam and consequently the supplemental needle raising cam 8 is down out of operation. When the lever 35 falls into the space 37 and on to the low part at this point, the said cam 8 will be raised. Springs 38 and 39 act upon the levers 21 and 35.

The widening picks, as usual, are under tension of springs, one of which is indicated at 40. These tend to swing the picks upwardly at an inclination, their axes being inclined. The picks are pressed down out of operative, or elevated, position by a controller 41, having arms overlying the pick stems, said controller being fixed to a block 42, guided vertically in a post 43 supported on the base of the knitting head. This block is fixed to a vertically movable rod 44, the lower end of which rests on a lever 45, pivoted to the bracket 46 at 47 and having an arm 48 to, which a link 49 is connected, the lower end of said link being connected to a lever 50 resting on a cam 51 fixed to the shaft s' . This cam is substantially of usual construction. If has, however, a block d inserted to extend the high part of this cam to hold the widening picks up for the formation of the diagonal gore by widening as above described. In usual practice the block is not present in the cam and the lever would fall into the space at the point e for narrowing at the heel. With the use of this block a change is made in the pattern

ratchet that moves this cam drum by the addition of a half tooth in the ratchet, which compensates for this difference in the width of the space e . This cam 51, as usual, has the low part e , into which the cam lever 50 falls, for the heel narrowings, the high part f for the heel widening, the space g for round knitting on the foot, the high part h which is skipped, the low part i for toe narrowing, the high part h' for toe widening, and the high part k for the leg. The cams are shown in the position assumed by them at the lower end of the leg just before the machine begins the formation of the diagonal gore.

For convenience of illustration I have shown the pattern cams and levers in a general way and diagrammatically in Fig. 3, the exact relative arrangement of these levers and cams to get the proper sequence of operations being within the skill of the ordinary mechanic or machine adjuster.

I claim:

1. In combination in a circular stocking knitting machine, a needle cylinder, narrowing and widening picks, heel and toe needles including a column of short butt needles and two columns of medium butt needles, one at each end of the column of short butt needles, instep needles having longer butts than the medium butt needles, a cam for elevating the long butt instep needles and the medium butt heel and toe needles at a point at the back of the stocking preceding the formation of the heel pocket, means for controlling the picking to widen on the medium butt needles at said point to make a diagonal gore extending to the point where narrowing begins for the heel pocket, then narrowing and widening on said heel and toe needles, and continuing the widening on the longer butt instep needles, a pivotally mounted raising cam for elevating only the longer butt instep needles, for the formation of the toe, a lowering cam to lower elevated needles, connections for raising said lowering cam independently of the pivotally mounted raising cam and means for operating said pivotally mounted cam independently of the raising cam first mentioned, which remains down during the formation of the toe, substantially as described.

2. In combination in a circular stocking knitting machine, a needle cylinder, narrowing and widening picks, instep needles having butts of a length to permit picking theron, heel and toe needles including a column of short butt needles, and two columns of medium butt needles, one at each end of the column of short butt needles, said medium butt needles having shorter butts than the instep needles, means for elevating the long butt instep needles and the medium butt heel and toe needles at a point in the leg preceding the heel pocket, means for con-

trolling the picking to widen on the medium butt needles at said point to make a diagonal gore extending to the point where narrowing begins for the heel pocket, then narrowing and widening on the said heel and toe needles, and continuing the widening on the longer butt instep needles, substantially as described.

3. In combination in a circular stocking
10 knitting machine, a needle cylinder, narrowing and widening picks, instep needles having butts of a length to permit picking thereon, heel and toe needles including a column of short butt needles and two columns of medium butt needles, one at each end of the short butt needles, a lowering cam for the instep and medium butt needles, a raising cam for the long butt instep needles with means for operating it independently
20 of the said lowering cam, and a supplemental raising cam for the instep needles and the medium butt heel and toe needles, and means to control the picking to widen for a diagonal gore preceding the heel pocket, narrowing and widening for the heel pocket and continued widening on the instep needles and to narrow and widen for the usual toe pocket, substantially as described.

4. In combination in a circular stocking
30 knitting machine, a needle cylinder, a series of instep needles having butts of a length to permit picking thereon, a series of heel and toe needles having two lengths of butts, a raising cam for elevating the long and medium butt needles prior to the formation of the heel pocket, pick mechanism with con-

trolling means for widening on the medium butt needles for making a diagonal gore preceding the heel pocket and the narrowings and widenings for the heel pocket and continue widening on the instep needles, a cam for raising the instep needles at the toe for the formation of the usual toe pocket on the other needles, substantially as described.

5. In combination in a circular stocking 45 knitting machine, a needle cylinder, a series of instep needles having butts of a length to permit picking thereon, a series of heel and toe needles having two lengths of butts, a raising cam for elevating the longer me- 50 dium butt needles prior to the formation of the heel pocket, pick mechanism with controlling means for widening on the medium butt needles for making a diagonal gore preceding the heel pocket, and then the nar- 55 rowings and widenings for the heel pocket and continue widening on the instep needles, a cam for raising the instep needles at the toe for the formation of the usual toe pocket on the other needles, a lowering cam for the 60 needles, said raising cam last mentioned, being located adjacent the said lowering cam and the said raising cam first mentioned being located adjacent the widening picks, sub- 65 substantially as described.

In testimony whereof, I affix my signature in presence of two witnesses.

GEORGE P. BOSWORTH.

Witnesses:

EUGENE M. GUNNING,
JOHN LAWSON.
